(57) **CLAIM**

The ornamental design for a display screen or portion thereof with animated-graphical user interface, as shown and described.

DESCRIPTION

FIG. 1 is a front view of a display screen or portion thereof with an animated graphical user interface showing a first image in the sequence;

FIG. 2 is a second image thereof;

FIG. 3 is a third image thereof;

FIG. 4 is a fourth image thereof;

FIG. 5 is a fifth image thereof; and,

FIG. 6 shows the fifth image in the environment of a display screen with graphical user interface.

The broken lines illustrate a display screen or portion thereof, and portions of a graphical user interface, and form no part of the claimed design. The appearance of the transitional image sequentially transitions between the images show in FIGS. 1-5. The process or period in which one image transitions to another image forms no part of the claimed design.
